UNITED STATES PATENT OFFICE

2,675,938

DISHWASHER CABINET CONSTRUCTION

Jacques Stanitz, Warren, Ohio, assignor to Mullins Manufacturing Corporation, Salem, Ohio, a corporation of New York

Application November 1, 1950, Serial No. 193,382

4 Claims. (Cl. 220—15)

1

The invention relates generally to cabinets for dishwashing machines, and more particularly to a cabinet construction for rigidly supporting the dishwasher tub independently of the cabinet top or the sink element forming the top of the cabinet. Certain features of the cabinet construction comprising the present invention are disclosed but not claimed per se in the co-pending applications of Jacques Stanitz, Myron E. Ullman, Jr., and John L. Habe, Serial No. 178,054, entitled Dishwashing Apparatus, filed August 7, 1950, and Serial No. 185,232, entitled Automatic Dishwashing Apparatus, filed September 16, 1950.

In certain prior dishwasher cabinets, the dishwasher tub is supported or secured at its top end on the cabinet top or sink element. Accordingly, when it is desired to remove the cabinet top, this cannot be done without disturbing the tub and the dishwasher elements connected thereto, so that it becomes necessary to break all plumbing and electrical connections and disassemble the various components. For these reasons, the assembly or re-assembly of such dishwasher tub and cabinet is a somewhat difficult and exacting operation.

Furthermore, it is desirable that the dishwasher tub be vented to allow a portion of the vapors to escape during the dishwashing operation when the lid is closed, and such venting is most effectively accomplished by providing a narrow annular vent between the tub and the dishwasher top. In prior dishwasher cabinets having the tub supported on the cabinet top, it is very difficult to provide for an annular vent between the tub and the cabinet top and still obtain a sufficiently rigid supporting connection between the same.

It is a general object of the present invention to provide a novel dishwasher cabinet construction rigidly and detachably supporting the dishwasher tub within the cabinet.

Another object is to provide a novel dishwasher cabinet rigidly supporting the dishwasher tub independently of the cabinet top.

Another object is to provide a novel dishwasher cabinet rigidly supporting the dishwasher tub and independently supporting a top element having a continuous inner rim portion extending within and spaced inwardly of the top portion of the tub.

A further object is to provide a novel cabinet construction having novel means which detachably supports the dishwasher tub within the top portion of the cabinet and which also braces the cabinet to improve its rigidity.

2

A still further object is to provide a rigid and lightweight dishwasher cabinet construction detachably mounting the dishwasher tub for quick assembly and removability independently of the cabinet top.

These and other objects are accomplished by the parts, constructions, arrangements, combinations and sub-combinations comprising the present invention, a preferred embodiment of which is shown in the accompanying drawings as exemplifying the best known mode of carrying out the invention, the invention being described in detail in the accompanying specification, and the scope of the invention being defined in the appended claims.

In general terms, the dishwasher cabinet construction of the present invention includes front, rear and side wall elements forming preferably a substantially rectangular cabinet, a tub support ring having outer portions secured to said wall elements within and below the top of said cabinet, said supporting ring having an inner annular flange, the upper rim of the dishwasher tub being detachably mounted on said flange, and there being a top member supported on top of the cabinet side wall elements and having an inner annular rim flange extending downwardly within the top portion of said tub and spaced inwardly thereof to form an annular vent between said tub and said inner annular rim flange.

Referring to the drawings forming part hereof, in which a preferred embodiment of the invention is shown by way of example:

Figure 1 is a front elevation, with parts broken away in section, of the novel dishwasher cabinet construction embodying the present invention;

Fig. 2 is a plan view, partly in section, as on line 2—2, Fig. 1;

Fig. 3 is a fragmentary plan sectional view as on line 3—3, Fig. 1;

Fig. 4 is an enlarged fragmentary sectional view as on line 4—4, Fig. 2;

Fig. 5 is an enlarged fragmentary sectional view as on line 5—5, Fig. 2; and

Fig. 6 is a vertical sectional view, as on line 6—6, Fig. 2.

Similar numerals refer to similar parts throughout the drawings.

The novel cabinet of the present invention may be supported on a suitable base indicated generally at 7, and the base may be of any suitable design and construction, and forms no part of the present invention. The novel cabinet preferably includes sheet metal vertical side walls 8 and 9, forming opposite sides of a substantially

rectangular cabinet, the rear edges of the side walls preferably being bent at right angles toward each other to form vertically extending flanges 10 and 11 extending from top to bottom of the side walls.

The front edges of the side walls 8 and 9 may be formed into ornamental corner portions 12 and 13, substantially S-shaped in cross section and having recessed shoulder portions 12a and 13a terminating in angular vertically extending flanges 14 which have widened portions 14a at the top and widened portions 14b at the bottom. The widened portions 14b may be welded to a sheet metal floor or platform member indicated generally at 15, and as shown in Fig. 3, the floor member 15 is cut to fit substantially within the ornamental members 12 and 13, and may have downturned flanges 16 (Fig. 6) engaging within the side wall members 8 and 9, thus rigidly bracing the side wall members. As shown in Fig. 6, the floor member 15 may rest on inturned angular flanges 17 at the bottom edges of the side wall members 8 and 9.

The top edges of the side wall members 8 and 9 are preferably provided with inwardly turned flanges 18 providing shoulders for supporting the sink or cabinet top indicated generally at 19. As shown, the cabinet top 19 may include a conventional splash back 20 and a horizontal rim portion 21 having downwardly extending outer rim flanges 22 terminating in inturned bead flanges 23 which rest on a gasket 24 on the seating flanges 18, and which engage upturned lips 25 formed on the inner edges of flanges 18 to position the top 19 in place. Inturned top flanges 26 are provided on the corner portions 12 and 13, in the same plane as flanges 18.

As shown in Fig. 3, horizontal gusset plates 27 may be secured as by welding to the flanges 18 and 26 to tie them together at the front corners. Likewise, gusset angles 28 (Fig. 6) may be secured as by welding in the rear corners between the vertical flanges 10 and 11 and the top flanges 18 at the rear edges thereof. Preferably, a pair of diagonal strap braces 29 and 30 is provided extending across the back side of the cabinet, said braces being preferably spot welded at their upper and lower ends to upper and lower portions of the flanges 10 and 11. A rear reinforcing angle 31 having a lower horizontal flange 31a extends transversely between the rear flanges 10 and 11 and has its ends spot welded thereto at points spaced below the gusset angles 28.

A front mounting channel 32 extends horizontally transversely between the vertical flanges 14, immediately below the widened portions 14a, and the ends 33 of the web of channel 32 preferably extend rearwardly and then outwardly behind the flanges 14, and are spot welded thereto. The channel web may support an upper front panel 34 by means of suitable bolts extending through holes 35 in said channel. Also, the channel 32 may have a central recessed portion 36 adapted for supporting a control mechanism operated by a knob 37 located in front of an escutcheon plate 38 on said panel 34.

A strike channel 39 extends horizontally transversely between the shoulders 12a and 13a behind the bottom of said panel 34, and the ends 40 of the web of said channel preferably extend in front of the vertical flanges 14 and may be spot welded thereto. The channel 39 forms a strike or abutment for the upper edge of a door 41 having a handle 42. The door 41 may be suitably hinged on the shoulder 13a for swinging closely

adjacent to the shoulder 12a of corner portion 12.

Thus the side walls 8 and 9 of the cabinet are rigidly connected at their bottom ends by the floor member 15, and at their upper ends by front channel 32 and rear angle 31. The channel 32 may be termed a front wall element and the angle 31 may be termed a rear wall element. In addition, the side walls 8 and 9 are rigidly connected at their rear edges by diagonal braces 29 and 30 and their upper rear corners are reinforced by gusset angles 28. Also, the upper front corners are reinforced by gusset plates 27, and the vertical flanges 14 at the front of the corner portions are rigidly connected to the strike channel 39 adjacent their top ends and to the floor member 15 at their bottom ends.

This construction provides a solid and rigid cabinet independently of the cabinet top 19, which merely sets on the top ends of the side walls and corner portions, and which may be detachably connected to the widened portions 14a by depending angle brackets 44 spot welded to the cabinet top and attached to the portion 14a by bolts 45.

The dishwasher tub indicated generally at 47 is preferably round having a substantially cylindrical side wall 48 merging with a downwardly sloping bottom wall 49 having a well 50 in its central portion. However, other shapes and designs of tubs may be used within the scope of the present invention. The side walls of the tub 47 are formed at their upper ends with an outwardly flange terminating in a downturned circumscribing flange 51 forming a U-shaped channel, and the flange 51 in the case of a round tub is round or annular.

The means for detachably supporting the tub 47 preferably includes a ring member indicated generally at 52 having a central opening formed by an inner upstanding annular flange 53 telescoped within and engaging under the tub flange 51 in the U-shaped channel. The tub flange 51 and ring flange 53 are detachably connected together at circumferentially spaced points by bolts 54. Preferably the nuts 55 for the bolts are welded or otherwise secured to the inner surface of the flange 53 in register with the bolt holes, so that the bolts can easily be attached or detached without holding the nuts. As indicated in Fig. 2, four bolts 54 are located adjacent the corners of the cabinet so as to be easily accessible.

The inner annular flange 53 of ring member 52 preferably curves outwardly downward and merges with a horizontal plate portion 56 having preferably four rectangularly disposed sides with downturned outer flanges. The two flanges 51 at opposite sides are secured as by welding to the cabinet side walls 8 and 9, the rear flange 53 is welded to the rear angle 31 and preferably rests on the bottom leg 31a thereof, and front flanges 59 are welded to the web of front channel 32 on opposite sides of recessed portion 36 and rest on the bottom leg or flange of said channel. As shown in Figs. 2 and 3, the front corners of the plate 56 may be cut off diagonally and provided with downturned flanges 60 connecting the side flanges 57 with the front flanges 59, and the rear corners cut off and provided with downturned flanges 61 connecting the side flanges 57 with the rear flange 58. Thus the outer periphery of the ring member is octagonal.

The ring member 52, being rigidly secured to all four sides of the cabinet, provides means rigidly reinforcing the upper portion of the cabinet, in addition to the other bracing and re-

inforcing means already described. Accordingly, the ring member 52 serves the dual purpose of reinforcing the cabinet and solidly mounting the tub.

The cabinet top 19 may have an inner ledge or shoulder 63 on which a suitable lid (not shown) seats for closing the top of the tub during the dishwashing operation. As shown, the outer edge of said shoulder 63 may be connected to the rim portion 21 by a vertical flange 64 extending continuously around the cabinet top in the form of a rectangle with rounded corners. Obviously, the lid would be similarly formed to fit within the flange 64.

The inner edge of shoulder 63 is connected to a downturned flange 65 extending continuously around the shoulder and cylindrical in form to fit closely within the upper portion of the tub wall 48, thus defining the access opening to the tub. The flange 65 extends downwardly a substantial distance so as to extend well within the upper portion of the tub, and the bottom edge of the flange is preferably turned radially outward toward the tub wall 48 so as to provide a narrow annular vent between the tube and cabinet top as indicated at 66. This vent is desirable to provide for the escape of vapors within the tub without allowing the washing medium to escape. Otherwise, the vapor pressure might build up within the tub and make it difficult to close the lid or tend to bulge the lid if it were locked in closed position.

In assembling the tub within the novel cabinet before the top 19 is applied, the tub is lowered within the top of the cabinet, which has the supporting ring 52 already welded in place, and the tub rim flange 51 is engaged over flange 53. The tub is rotated to bring the bolt holes in flange 51 into register with nuts 55 and the bolts 54 are screwed into the nuts, whereupon the tub is solidly mounted within the cabinet. The top 19 may then be seated on the gasket 24, and the brackets 44 connected to flange portions 14a by bolts 45. If it should be desired to later remove the top 19, this may be done merely by removing bolts 45, without in any way disturbing the tub or tub mounting means.

The novel cabinet construction rigidly and detachably supports the dishwasher tub within the cabinet independently of the cabinet top having a depending inner rim flange extending within and spaced inwardly of the tub, and the tub supporting means also braces the cabinet to increase its rigidity. Moreover, the tub is mounted for quick assembly and removability in simple and lightweight cabinet construction.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical equivalents thereof obvious to those skilled in the art, are set forth in the appended claims.

I claim:

1. In cabinet dishwasher construction, a rectangular sheet metal cabinet having front, rear and side wall elements rigidly connected together, certain of said wall elements being provided with inturned flanges at their upper ends, a tub support ring means spaced below said inturned flanges rigidly secured to said cabinet wall elements, said tub support ring means being formed with a central opening and having an upturned flange surrounding said opening, a tub member having side walls formed at their upper ends with an outturned flange terminating in a downturned circumscribing flange forming a U-shaped channel, said downturned tub flange being telescoped over said upturned tub support ring means flange with the ring means flange seated in the U-shaped channel, detachable means rigidly securing said telescoped upturned and downturned flanges together, a cabinet top member having side rim flange portions terminating in inturned flange means resting on said inturned cabinet wall flanges and supported by the cabinet walls independently of said tub and tub support ring means, and said cabinet top member being provided with a tub access opening formed by a downturned flange telescoped within the tub side walls and spaced inwardly therefrom forming an annular vent between the top member flange and the tub side walls.
2. The construction as defined in claim 1, in which the upturned flange on the tub support ring means is circular, in which the tub has circular side walls, and in which the downturned flange at the upper end of the tub side walls telescoped over the upturned tub support ring means flange is circular.
3. The construction as defined in claim 1, in which the front and rear cabinet wall elements comprise flanged members extending horizontally between the cabinet side wall elements, and in which the tub support ring means rests on the flanges of said front and rear horizontally extending cabinet wall elements.
4. The construction as defined in claim 1, in which depending angle brackets are attached to the cabinet top member, and in which means is provided detachably connecting said angle brackets with certain cabinet wall elements.
